INDICATOR

William L. Maxson, Pipestone, Minn.

Application December 15, 1933, Serial No. 702,470

6 Claims. (Cl. 40—70)

This invention relates to indicators and has for its object a simple, compact, inexpensive and easily operable indicator which will give direct readings of relationships existing between a group 5 of units listed on the indicator.

The units of the indicator may be any which have a definite relationship existing between them. By way of example, the invention is specifically disclosed as an indicator of distances 10 between any two cities of a selected group of cities. In this example, the cities are the units. However, the indicator is adaptable for use in connection with any group of units having a fixed relationship existing therebetween.

15 Other objects, novel features and advantages of this invention will be apparent from the following specification and accompanying drawings, wherein:

Fig. 1 is a plan view of an apparatus embodying 20 the invention;

Fig. 2 is a section on the line 2—2 of Fig. 1;

Fig. 3 is a plan view of the intermediate disk, and

Fig. 4 is a plan view of the bottom disk. 25 A top disk 10, an intermediate disk 11 and a bottom disk 12 are held together for relative rotary movement by a rivet or the like 13. The disk 10 is provided with a spiral slot 14 which preferably is an Archimedean spiral. On the 30 periphery of the disk 10 is provided a series of uniformly spaced reference lines 15 which define equal segments. On the disk 12 is arranged a succession of spiral lines of numbers, each line of numbers being of the same configuration as 35 the slot 14 and so arranged that each line of figures is capable of registration with the slot 14. There are as many spiral lines of numbers as there 40 are reference lines 15 and the first numbers in the successive spirals define a circle concentric with the three disks. The disk 11 is provided with a series of windows 16 which correspond 45 successively to sections of the slot 14 having the same length of arc as the above mentioned segments. The windows are so arranged that rotation of the disk 10 through successive segments 50 effects rotation of the windows with their corresponding slot sections. The numbers in the spiral lines are so spaced that with the slot 14 overlying said line of numbers, the numbers are 55 successively visible upon registration of successive windows 16 with their corresponding slot portions.

Many of the windows are not physically separate from each other, but each window cooperates with the slot 14 to function independently

of the other windows. Disks 11 and 12 are provided respectively with tabs 17 and 18 provided with reference lines 17a and 18a adapted for registration with the reference lines 15 on the disk 10.

The embodiment of the invention herein specifically disclosed is a device for indicating the distance between any two given cities of a predetermined group of cities. The various city names are arranged in alignment with the reference lines 15. The various numbers in each of the spiral lines of numbers reading outward represent respectively distances between a given listed city and all the listed cities, including itself, reading clockwise of the disk 10. One spiral starts with zero and the remaining spirals are so arranged that the series of numbers of the inner circle reading counter-clockwise from the zero is the same as the series of numbers on said spiral reading outwardly.

The reference line 18a is so arranged that when it registers with the reference line 15 of a predetermined city, Washington in this instance, the slot 14 overlies the spiral starting with zero. The reference line 17a is so arranged that when it is in register with the reference line 18a, the innermost window 16 registers with the zero of the inner circle of numbers on the disk 14, and it follows that by reason of the succession of windows in the various spirals, each successive window 16 in such position of the disks 12 and 13 registers with the zeros in the successive spirals so that whenever the reference lines 17a and 18a are in register with the same reference line 15, the indicator shows zero distance.

In the use of the above described device, the disks 11 and 12 are rotated relative to the disk 10 by means of the tabs 17 and 18 to bring the reference lines 17a and 18a into registration with the reference line 15 of the two cities, the distance between which it is desired to find out. The number representing such distance will be visible through the slot 14 and a window 16 and may be read off directly. The lines of numbers on the disk 12 preferably follow an Archimedean spiral as such spiral permits complete coverage of the bottom disk with lines of numbers of equal height throughout. Other spirals do not permit complete coverage by lines of numbers of equal height.

As previously pointed out, the invention is not limited to an indicator of distances between cities, but is adapted for use to indicate fixed relationships existing between individual units of a group of selected units. Furthermore, an indicator em-

bodying the invention may comprise merely the disks 10 and 12. In such an indicator, a complete spiral of numbers or other data becomes visible upon registration of the reference line 18a with a reference line 15 and the data in the spiral lines bear a definite relationship to the units corresponding to the different reference lines 15.

It is, of course, apparent that various modifications may be made without in any way departing from the spirit of the invention as defined in the appended claims.

I claim:

1. A device of the character described comprising three superposed concentric disks connected together for relative rotation, the upper disk having a spiral slot and having uniformly spaced reference points along its periphery representing units, the lower disk having an equal number of lines of numbers arranged along curves identical with said spiral slot, the numbers in each line representing relationships between a given unit and all the units, and reference lines on the middle and lower disks, the middle disk having a series of windows successively corresponding to successive equal portions of said spiral slot and so arranged that a window registers with the slot over the number representing the relationship between two units when the reference lines on the lower and middle disks are in register with reference lines on the upper disk representing said units.

2. A device of the character described comprising three superposed concentric disks connected together for relative rotation, the upper disk having a spiral slot and uniformly spaced reference lines about its periphery representing units, the lower disk having an equal number of lines of numbers arranged along curves identical with said spiral slot, the numbers in each line representing relationships respectively between a given unit and all the units, reference lines on the middle and lower disks, the middle disk having a series of windows successively corresponding to successive equal sections of said slot, said windows being so arranged that upon rotation of the middle disk relative to the upper disk the windows register successively with corresponding portions of the slot upon registration of the middle disk reference line with successive reference lines on the upper disk and the numbers of each spiral line being so arranged that with the spiral slot in registration therewith, the windows register with said numbers successively upon registration of the middle disk reference line with successive upper disk reference lines.

3. A device of the character described comprising three superposed concentric disks connected together for relative rotation, the upper disk having a spiral slot and uniformly spaced reference lines about its periphery representing units, the lower disk having an equal number of lines of numbers arranged along curves identical with said spiral slot, the numbers in each line representing relationships respectively between a given unit and all the units, reference lines on the middle and lower disks, the middle disk having a series of windows successively corresponding to successive portions of said slot and corresponding to successive equal sections of said slot, said windows being so arranged that upon rotation of the middle disk relative to the upper disk the windows register successively with corresponding portions of the slot upon registration

of the middle disk reference line with successive reference lines on the upper disk and the numbers on the lower disk being so arranged that a spiral line of numbers underlies the upper disk slot upon registration of the lower disk reference line with any upper disk reference line.

4. A device of the character described comprising three superposed concentric disks connected together for relative rotation, the upper disk having an Archimedean spiral slot and having uniformly spaced reference points along its periphery representing units, the lower disk having an equal number of lines of numbers arranged along curves identical with said spiral slot, the numbers in each line representing relationships between a given unit and all the units, and reference lines on the middle and lower disks, the middle disk having a series of windows so arranged that a window registers with the slot over the number representing the relationship between two units when the reference lines on the lower and middle disks are in register with reference lines on the upper disk representing said units.

5. A device of the character described comprising three superposed concentric disks connected together for relative rotation, the upper disk having an Archimedean spiral slot and uniformly spaced reference lines about its periphery representing units, the lower disk having an equal number of lines of numbers arranged along curves identical with said spiral slot, the numbers in each line representing relationships respectively between a given unit and all the units, reference lines on the middle and lower disks, the middle disk having a series of windows successively corresponding to successive equal sections of said slot, said windows being so arranged that upon rotation of the middle disk relative to the upper disk the windows register successively with corresponding portions of the slot upon registration of the middle disk reference line with successive reference lines on the upper disk and the numbers of each spiral line being so arranged that with the spiral slot in registration therewith, the windows register with said numbers successively upon registration of the middle disk reference line with successive upper disk reference lines.

6. A device of the character described comprising three superposed concentric disks connected together for relative rotation, the upper disk having an Archimedean spiral slot and uniformly spaced reference lines about its periphery representing units, the lower disk having an equal number of lines of numbers arranged along curves identical with said spiral slot, the numbers in each line representing relationships respectively between a given unit and all the units, reference lines on the middle and lower disks, the middle disk having a series of windows successively corresponding to successive equal sections of said slot, said windows being so arranged that upon rotation of the middle disk relative to the upper disk the windows register successively with corresponding portions of the slot upon registration of the middle disk reference line with successive reference lines on the upper disk and the numbers on the lower disk being so arranged that a spiral line of numbers underlies the upper disk slot upon registration of the lower disk reference line with any upper disk reference line.

WILLIAM L. MAXSON.

CERTIFICATE OF CORRECTION.

Patent No. 2,042,615.

June 2, 1936.

WILLIAM L. MAXSON.

It is hereby certified that error appears in the printed specification of the above numbered patent requiring correction as follows; Page 2, first column, line 68-69, claim 3, strike out the words "portions of said slot and corresponding to successive"; and second column, line 18, claim 4, after "windows" insert the words "successively corresponding to successive portions of said slot and"; and that the said Letters Patent should be read with these corrections therein that the same may conform to the record of the case in the Patent Office.

Signed and sealed this 18th day of August, A. D. 1936.
